WATER TRAVERSING AIR CUSHION VEHICLE
Melville W. Beardsley, Severna Park, Md., assignor, by
mesne assignments, to National Research Associates,
Inc., Laurel, Md., a corporation of Maryland
Filed Feb. 28, 1961, Ser. No. 99,006
11 Claims. (Cl. 114—67)

The present invention relates to an air cushion vehicle especially adapted to travel over water, and has particular reference to an improved type of air cushion vehicle for use over water and certain types of terrain, particularly that terrain that might be found adjacent to bodies of water.

Accordingly, the present invention is directed to a craft that can travel conveniently over deep or shallow water, in weed filled waters, and can also pass over mud banks, wet sand, and even dry surfaces which are relatively smooth.

The present invention is also commercially attractive in that it can eliminate the use of expensive docking facilities through its ability to pass onto and over flat dry surfaces.

In the new type vehicle of this invention there is no draft required thus providing advantages of decreased resistance or drag as compared with boats of conventional or hydrofoil design.

Also, the vehicle of this invention will not encounter the difficulties inherent with propellers on conventional boats such as damage sustained by striking obstacles or debris in the water and weed fouling.

Furthermore, the vehicle of the present invention through the use of the novel mechanical design disclosed allows the building of a lighter structure and the obtaining of higher speed with the use of less power.

Basically, the present invention provides a novel and improved vehicle which can ride over the surface of water with a minimum of surface friction and wave drag.

These as well as further advantages which are inherent in the invention will become apparent from the following description, reference being had to the accompanying drawings, wherein:

FIG. 1 is a perspective view of an embodiment of the vehicle of this invention;

FIG. 2 is a partially cut away side elevation view of the vehicle of the present invention, sectioned as seen substantially on line 2—2 of FIG. 3;

FIG. 3 is a top plan view of the vehicle;

FIG. 4 is a rear elevation view;

FIG. 5 is a front elevation view;

FIG. 6 is a perspective partial bottom view of one of the runners showing detail.

With particular reference now to the figures, there is illustrated a mechanical embodiment of the features of the present invention wherein FIG. 1 is a perspective view of an air cushion vehicle which may be used primarily for travel over water but which can also travel over dry hard smooth terrain.

In FIG. 1 there is depicted the general configuration of the vehicle of the present invention. Hull 10 is shown with the placement of fans 11 in the forward part of hull 10 but below the deck 12. In the rear of hull 10 other fans 13 of a larger variety than fans 11 are also placed below the deck 12. The bow of hull 10 is composed of a flexible sheet material 14 supported by a heavy foam rub-

2

ber or plastic section 15 which is merely an extension of deck 12. In the picture of the vehicle in FIG. 1 the flexible material 14 is shown as it would appear when inflated by air from fans 11. The relationship of the fans and the flexible bow to the rest of hull 10 is also depicted in the top plan view designated as FIG. 3.

FIG. 2 is a partial cut away view of the vehicle of this invention showing the internal structure of hull 10. As shown in this figure by arrows which designate the flow of air fan 11 takes in air through ports 21 and blows this air into the tunnel plenum 19 under hull 10. Some of this air takes the path toward the forward part of hull 10 and passes through flexible material 22 having holes therethrough. This air passing through flexible material 22 enters an air chamber behind the flexible bow 14 and inflates it to a rounded shape allowing it to act as a cushion against shock caused by impact of the water which may occur during the forward motion of the vehicle in rough water. The heavy layer of foam rubber 15 which is the extension of deck 12 allows this bow 14 to deflect under impact and yet to keep its shape even when no air is pumped into this section.

Some of the air from fans 11 enters an opening at the forward end of conduit 23 and passes through this conduit to inflatable-structure flaps 24 located toward the rear of the vehicle. The amount of air entering the inflatable-structure flaps 24 is controlled by valve 25 in conduit 23 which is under the control of the operator of the vehicle. Inflatable flaps 24 have an escape outlet 26 as shown in FIG. 2 making it possible to vary the pressure in flaps 24 by varying the relationship of the flow area through valve 25 to the flow area of the escape outlet 26.

Fans 13 in the rear of the vehicle draw in a large volume of air and pass some of this air out under the rear of hull 10 and a portion out between louvres 27 located in the rear as shown, when these louvres are in an open position.

The sides of hull 10 extend downward in the form of skegs or runners 41 and 42, fixed at the bottom of hull 10 and running longitudinally and enclosing the sides of the plenum beneath hull 10 as depicted in FIGS. 4 and 5. An additional runner 43 is located under the hull running longitudinally along the center of the bottom. Although runner 43 is depicted here as a solid section, with air being piped to the inflatable flaps 24 through a conduit 23, another embodiment not shown would allow the air to pass through a semi-hollow center runner 43 to inflatable flaps 24.

Rudders 44 and 45 used to control the directional movement of the vehicle are located at the rear extremity of runners 42 and 41, respectively. On the forward part of each of the side runners 41 and 42 there is located one or more small planing surfaces or hydrofoils 51 extending from the inside surface of the runners with a small angle of inclination to the horizontal plane along the surface of the water over which the vehicle may travel. Hydrofoils 51, shown in this example only on the inside surface of the runners 41 and 42 may be located with like effect on the outside surface of these runners or other longitudinal positions on the lower sections of the runners whereby the hydrofoils may improve longitudinal stability in addition to lateral stability. Center runner 43 may also have planing surfaces or hydrofoils 51 located on both sides of that runner and also in the forward section of the vehicle.

FIG. 6 shows an enlarged bottom view of one of the runners. As shown, the runners have a series of swept-back planing surfaces 61 which deflect the air passing from the plenum outwardly under the runner in a generally rearward direction so that some thrust is derived from the escaping air. This series of planing surfaces 61 is only found on side runners 41 and 42, since it would have no effect if used on center runner 43.

In operation, the forward fans 11 are used basically to provide the plenum beneath hull 10 with air having a positive static pressure which, acting upward on the under surface of hull 10, provides a force which lifts the vehicle clear of the surface over which it travels. As stated before the air from fans 11 also provides for the inflation of flexible bow 14 for a cushioning effect. Under desired operating conditions some of the air from these fans escapes out under runners 41 and 42 through the open areas between the planing surfaces 61 and the water or ground surface beneath them. The remainder is discharged rearward through the opening between the bottom of inflatable flaps 24 and the surface over which the vehicle is traveling. Control of this open area determines the pressure under the vehicle and the height at which it operates and the amount of thrust developed.

Inflatable flaps 24 which are also supplied with air from fans 11 are used to accomplish trim control for the occasions where the vehicle is carrying a laterally off-center load. The supply of air to these flaps is individually controlled by valves 25. The inflation of each flap is controlled to provide the desired amount of open area for the discharge of air from under each side of hull 10 so as to cause any desired pressure difference to compensate for laterally offcenter loads.

The propulsion for this vehicle is provided mainly by the larger fans 13 which are located at the rear of the hull and usually designed to handle a greater air flow than forward fans 11. Through control of the discharge flow from these fans the pitch and trim of the vehicle may be changed where desired and the speed may be further controlled. The discharge flow area and direction may be controlled by the louvres 27 in the rear of the vehicle which may be opened or closed as desired. When a minimum nose down pitch moment is desired, louvres 27 are moved to their open position thereby allowing free air flow out of the hull from the rear fans with a large horizontal component of velocity. As the louvres are moved to a closed position, there is an increasing nose down pitching moment imparted to the hull 10 due to the downward discharge of the air flow and the buildup of pressure beneath fans 13 and the rear of hull 10. It is possible to develop sufficient pressure with these rearward located fans to provide lift for the entire vehicle, although in the embodiment shown, the lift pressure is supplied by air from front located fans.

A center skeg 43 is incorporated to divide the air space under the hull into two longitudinal parts to provide lateral stability. If one side is depressed from an equilibrium condition the air escape area at the rear, under inflated flap 24, and along the side under planing surfaces 61, is reduced so that the pressure under the low side is increased to provide a correcting moment. Lateral stability is further enhanced by the planing or hydrofoil surfaces 51, since the surface 51 on the low side is immersed deeper than the surface 51 on the high side and thus produces more lift to produce a corrective moment.

The vehicle is steered by rudders 44 and 45, located at the rear of runners 42 and 41, respectively. These rudders have a generally trapezoidal shape and are hinged at their forward edge. Due to the shape and the manner in which they are attached to the respective runners, there is no portion of the rudder below the bottom surface of the runner when the rudder is in a straight back position. This enables the vehicle to travel over a smooth hard surface without a scraping of the rudder. Since the hinged edge slants forward and upward, it will be noted that as

the rudder is turned its trailing edge moves to an increasingly lower level causing greater effectiveness due to the larger area in contact with the water. The upper inner surface of rudders 44 and 45, being in contact with the discharged air flow, also provides turning moment due to the deflection of this air flow.

A preferred embodiment of the invention has been described above. Various changes and modifications, however, may be made within the scope of the invention as set forth in the appended claims. Accordingly, reference should be made to these claims in determining the full scope of the invention.

What is claimed is:

1. An air cushion vehicle for travel primarily over water comprising a hull having a horizontal bottom, longitudinal vertical wall members extending downwardly from the sides and below the horizontal bottom of said hull, a first means for blowing air under the generally forward part of said hull, a second means for blowing air under the generally rear part of said hull, an inflatable lateral member extending downwardly below the horizontal bottom of said hull and between said longitudinal wall members, and substantially downwardly opening exhaust means in said inflatable member for controlling the air pressure therein thereby controlling the height of the lower edge of said lateral member.

2. An air cushion vehicle for travel primarily over water comprising a hull, a plurality of wall members located longitudinally along the bottom of said hull, one of said wall members located along the port side of the bottom of said hull and another of said wall members located along the starboard side of the bottom of said hull, at least one inflatable structure located under said hull, one said inflatable structure located transversely in the space between a pair of said wall members, means to supply air to said inflatable structure, and valve means to control the amount of air supplied to each of said structures, each of said inflatable structures having an exhaust means through which some of the air supply continually leaves said structure.

3. An air cushion vehicle for travel primarily over water comprising a hull, a plurality of wall members located longitudinally along the bottom of said hull, a first means for blowing air under the generally forward part of said hull, a second means for blowing air under the generally rear area of said hull, and rudder means for steering said hull when over water attached to the rear end of a longitudinal wall member and shaped generally in the form of a trapezoid, said rudder having a sloping hinge line along the forward edge of said rudder with the top of said hinge line in a forward position in relation to the bottom of said hinge line whereby turning of said rudder moves part of said rudder below the surface plane upon which said wall members travel and with said rudder in a straight back position all parts of said rudder are above the surface plane upon which said wall members travel thereby allowing for travel over a hard surface.

4. An air cushion vehicle for travel primarily over water comprising a hull, a plurality of vertical wall members located longitudinally along the bottom of said hull, one of said vertical wall members located along the port side of the bottom of said hull and another of said vertical wall members located along the starboard side of the bottom of said hull, a first means for blowing air under the generally forward part of said hull, a second means for blowing air under the generally rear area of said hull, at least one inflatable structure located under said hull, one said inflatable structure located transversely in the space between a pair of said vertical wall members, means to supply air to said inflatable structure, valve means to control the amount of air supplied to said inflatable structure, said inflatable structure having an exhaust means near its bottom through which some of the air supply continually leaves said structure.

5. An air cushion vehicle for travel primarily over

water comprising a hull, a plurality of generally vertical wall members located longitudinally along the bottom of said hull, one of said wall members located along the port side of the bottom of said hull and another of said wall members located along the starboard side of the bottom of said hull, a first means for blowing air under the generally forward part of said hull, a second means for blowing air under the generally rear area of said hull, at least one inflatable structure located under said hull, one said inflatable structure located transversely in the space between a pair of said wall members, means to supply air to said inflatable structure, said inflatable structures having an exhaust means near its bottom through which some of the air supply continually leaves said structure, and louvres mounted in the rear of said hull and opening toward the rear of said hull whereby additional control of pitch of said hull and forward motion may be obtained.

6. An air cushion vehicle for travel primarily over water comprising a hull, a plurality of runners located longitudinally along the bottom of said hull, one of said runners located along the port side of the bottom of said hull and another of said runners located along the starboard side of the bottom of said hull, a first means for blowing air under the generally forward part of said hull, a second means for blowing air under the generally rear area of said hull, at least one inflatable structure located under said hull, one said inflatable structure located transversely in the space between a pair of said runners, means to supply air to said inflatable structure, said inflatable structure having an exhaust means through which some of the air supply continually leaves said structure, rudder means for steering said hull attached to the rear end of a runner and generally in the form of a trapezoid, said rudder having a sloping hinge line along the forward edge of said rudder with the top of said hinge line in a forward position in relation to the bottom of said hinge line whereby turning of said rudder moves part of said rudder below the surface plane upon which said runners travel and with said rudder in a straight back position all parts of said rudder are above the surface plane upon which said runners travel thereby allowing for travel over a hard surface.

7. An air cushion vehicle for travel primarily over water comprising a hull, a plurality of vertical wall members located longitudinally along the bottom of said hull, one of said wall members located along the port side of the bottom of said hull and another of said wall members located along the starboard side of the bottom of said hull, a first means for blowing air under the generally forward part of said hull, a second means for blowing air under the generally rear area of said hull, at least one inflatable structure located under said hull, one said inflatable structure located transversely in the space between a pair of said wall members, means to supply air to said inflatable structure, said inflatable structure having an exhaust means near its bottom through which some of the air supply continually leaves said structure, and planing surfaces located in a substantially horizontal plane and attached to said wall members in a generally perpendicular direction to said wall members.

8. An air cushion vehicle for travel primarily over water comprising a hull having a plenum chamber therein with vertical longitudinal and transverse walls, at least one of said walls being flexible, means for blowing air into said plenum chamber, one of said vertical longitudinal wall members located along the port side of the bottom of said hull and another of said vertical longitudinal wall members located along the starboard side of the bottom of said hull, said pair of vertical wall members located in a longitudinal direction along the starboard and port bottom edges of said hull having a generally sawtooth shape on their bottom surfaces, said sawtooth shaped bottom surface having the outside of the lower portion of the tooth edge aft of the inner portion whereby

air may pass out through the recessed portions of the sawtooth shaped surface in a generally rearward direction.

9. An air cushion vehicle for travel primarily over water comprising a hull, a plurality of vertical wall members located longitudinally along the bottom of said hull, means for blowing air under said hull, a flexible bow section attached to the forward part of said hull and forming the bow of said hull, and a flexible element connecting between said flexible bow section and said hull to form a chamber bounded by said element, said bow section, and said hull and having an opening therethrough whereby some of the air passing under said hull may pass through the opening into said flexible inflatable bow section of said hull and thereby form a bow having a cushioning effect against impact of forces hitting against said hull during forward motion of said hull.

10. An air cushion vehicle for travel primarily over water with directional controls comprising a deflectable member in the rear of the vehicle in the path of air flow of the air cushion vehicle with a lower rear extremity which descends as it is horizontally deflected, said deflectable member having a sloping hinge line along the forward edge of said member with the top of said hinge line in a forward position in relation to the bottom of said hinge line.

11. An air cushion vehicle for travel primarily over water comprising a hull, a plurality of vertical wall members located longitudinally along the bottom of said hull, one of said vertical wall members located along the port side of the bottom of said hull and another of said vertical wall members located along the starboard side of the bottom of said hull, said pair of vertical wall members located in a longitudinal direction along the starboard and port bottom edges of said hull having a generally sawtooth shape on their bottom surfaces, said sawtooth shaped bottom surface having the outside of the lower portion of the tooth edge aft of the inner portion whereby air may pass out through the recessed portions of the sawtooth shaped surface in a generally rearward direction, a first means for blowing air under the generally forward part of said hull, a second means for blowing air under the generally rear area of said hull, at least one inflatable flap located under said hull, one said inflatable flap located transversely in the space between a pair of said vertical wall members, means to supply air to said inflatable flap, valve means to control the amount of air supplied to said flap, said inflatable flap having an exhaust means through which some of the air supply continually leaves said flap, louvres mounted in the rear of said hull opening toward the rear of said hull whereby additional control of pitch of said hull and forward motion may be obtained, rudder means for steering said hull attached to the rear end of a vertical wall member and shaped generally in the form of a trapezoid, said rudder having a sloping hinge line along the forward edge of said rudder with the top of said hinge line in a forward position in relation to the bottom of said hinge line whereby turning of said rudder moves part of said rudder below the surface plane upon which said vertical wall members travel and with said rudder in a straight back position all parts of said rudder are above the surface plane upon which said vertical wall members travel thereby allowing for travel over a hard surface, and a flexible inflatable bow section sheet attached to the forward part of said hull at its top and sides only and forming the bow of said hull, and a flexible element over the entrance to said bow section having an opening therethrough which permits passage of air into said bow section.
